UNITED STATES PATENT OFFICE

157,833

FRONT FENDER SKIRT OR SIMILAR ARTICLE

Harry Bookman, Los Angeles, Calif.

Application August 13, 1948, Serial No. 148,094

Term of patent 7 years

(Cl. D14—6)

To all whom it may concern:

Be it known that I, Harry Bookman, a citizen of the United States, residing in Los Angeles, in the county of Los Angeles, State of California, have invented a new, original, and ornamental Design for a Front Fender Skirt or Similar Article, of which the following is a specification, reference being had to the accompanying drawings, forming a part thereof.

Figure 1 is a perspective view of a front fender skirt showing my new design.

Figure 2 is a side elevational view thereof.

Figure 3 is a sectional view taken as on a line 3—3 of Figure 2.

Figure 4 is a sectional view taken as on a line 4—4 of Figure 2.

Figure 5 is a sectional view taken as on a line 5—5 of Figure 2.

Figure 6 is a sectional view taken as on a line 6—6 of Figure 2.

Figure 7 is a top view.

The dotted line showing in the several figures of the drawing is for illustrative purposes only.

I claim:

The ornamental design for a front fender skirt or similar article, substantially as shown and described.

HARRY BOOKMAN.
